UNITED STATES PATENT OFFICE.

IRVING H. FOWLE, OF MILWAUKEE, WISCONSIN.

SURGICAL INSTRUMENT.

Application filed March 23, 1923. Serial No. 627,019.

To all whom it may concern:

Be it known that I, IRVING H. FOWLE, a citizen of the United States, and resident of Milwaukee, in the county of Milwaukee, and State of Wisconsin, have invented certain new and useful Improvements in Surgical Instruments; and I do hereby declare that the following is a full, clear, and exact description thereof.

10 The invention pertains to improvements in vaginal washers and has primarily for its object the provision of a simple and efficient device of this character adapted to thoroughly flush the vaginal cavity as well as wipe the walls thereof, to remove all secretitious matter, and obtain a healthy and hygienic condition.

15 A further object is to provide a washer of the foregoing character, which, due to its simplicity of operation, readily lends itself to the use of a patient and eliminates the necessity of treatment by one skilled in the medical profession.

20 Another object lies in the provision of a device of the above character, having its parts particularly designed to facilitate cleansing and sterilizing and to prevent the accumulation of foreign matter.

25 A still further object is to provide means whereby a wiping pad or sponge may be detachably connected to the washer, thus providing for the use of a new and properly sterilized pad for each operation.

30 With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

35 In the accompanying drawing is illustrated one complete example of the physical embodiment of the present invention constructed according to the best mode so far devised for the practical application of the principles thereof.

40 In the drawings:—

Figure 1 is an elevational view with parts broken away and in section to more clearly illustrate the structural details.

45 Figure 2 is a transverse sectional view taken on the line 2—2 of Figure 1.

50 Figure 3 is a fragmentary detail view

illustrating the means for detachably connecting the wiping pad.

Figure 4 is an end elevation of the device, and

55 Figure 5 is a detail fragmentary view.

Referring now more particularly to the accompanying drawings, the present invention includes a shield 6 provided with a centrally disposed sleeve 7 having its inner 65 end spherically formed at 8 to provide a substantially water tight universal bearing for the washer 9 whose outer surface is spherical in shape, thus forming a ball and socket joint. Adjustably mounted within 70 the washer 9 is a hollow tube 10 which is locked in adjusted position with relation to the washer by means of a set screw 11.

The inner end of the tube 10 is provided with a pair of oppositely disposed prongs 75 12 which are preferably formed by cutting out the material at opposite sides of the tube, as illustrated in Figure 5, and bending the cut-out portions outwardly. The prongs 12 thus formed have inwardly projecting 80 tines 13 and because of the resiliency of the prongs the same are capable of being contracted as the washer 14 mounted on the tube is forced over them. In their contracted position the tines of the prongs are 85 adapted to engage the wiping pad 15 which may be constructed of any suitable material, such as gauze, or a sponge.

The washer 9 is provided with an outlet 90 opening 16 for the purpose which will be later described, and the outer end of the tube 10 has connected thereto a rubber hose 17 connected with any suitable source of cleansing liquid supply which is fed to the wiping pad 15 and is discharged through 95 the openings 18 formed in the inner end of the tube. It will also be seen that a certain portion of the cleaning material will pass through the slots formed in the tube by the punching out of the prongs 12.

100 In the operation of the device, the sleeve 7 is inserted into the vaginal opening, the tube 10 having been previously adjusted to the desired position with relation to the shield. It may then be freely oscillated within 105 the limits indicated by dotted lines in Figure 1. During this operation the cleansing liquid is supplied to the tube 10 and discharged through the openings 18 into the vaginal cavity until such cavity is completely 110 filled, at which time the cleansing liquid will be discharged through the opening 16 pro-

vided in the washer 9, and inasmuch as the opening 16 is restricted in proportion to the fluid outlets provided in the end of the tube 10, the cleansing fluid will be held within 5 the vaginal cavity, thus insuring a complete and thorough flushing.

It will also be noted that the present invention, which provides for the attachment of the wiping pad to the end of the tube 10, 10 lends itself most effectively to the removal of secretitious matter from the cervix, at which point the greatest accumulation takes place, and as the device is withdrawn 15 from the vaginal cavity, a slight oscillation of the tube 10 will cause the pad to thoroughly wipe the walls thereof.

From the foregoing it will be seen that a very simple and efficient wiper has been provided which can be readily taken apart for 20 the purpose of sterilizing, and which can be easily operated by the patient herself without injury, leaving the vagina in a healthy and hygienic condition so essential to proper health.

25 A further advantage of the present device resides in the provision for detachably connecting the wiping pad to the tube, thus permitting the use of a new and properly sterilized pad for each operation.

30 I claim:—

1. A device of the character described, comprising a shield, a hollow tube universally mounted in said shield, a wiping pad detachably connected to one end of the tube, and means for supplying cleansing liquid to 35 said tube.

2. A device of the character described, comprising a shield provided with a bearing, a spherical washer universally journaled in said bearing and provided with an 40 offset opening, a hollow tube carried by the washer and provided with openings adjacent

its inner end, a wiping pad detachably connected to the inner end of the tube, and means for supplying cleansing liquid to the 45 opposite end of the tube.

3. A device of the character described, comprising a shield, a hollow tube universally mounted in said shield, a wiping pad for the inner end of said tube, prongs connected to the tube for detachably retaining 50 said wiping pad, and means for supplying cleansing liquid to the tube.

4. A device of the character described comprising a shield having an inwardly extending sleeve, a spherical socket in the inner end of said sleeve, a spherical washer journaled in said socket, a hollow tube carried by said washer, a wiping pad detachably connected to the inner end of said tube, and 55 means for supplying cleansing liquid to the other end of said tube.

5. A vaginal syringe comprising a rigid tube having a hose receiving end and a delivery end and having a delivery aperture 60 adjacent its delivery end, spring clips carried adjacent said delivery end of said tube and adapted to detachably receive a pad, a shield having a main body and a tubular portion through which said tube projects, 65 said tubular portion extending from the body of said shield towards the delivery end of said tube, and an apertured washer carried by and supporting said tube and socketed for universal motion within the end 70 of the tubular portion of said shield and at a point between the delivery end of said tube and the body of said shield.

In testimony that I claim the foregoing I have hereunto set my hand at Milwaukee, in 75 the county of Milwaukee and State of Wisconsin.

IRVING H. FOWLE.
